BOILER CONSTRUCTION

Filed July 24, 1930

UNITED STATES PATENT OFFICE

WILLET E. STARK, OF EAST CLEVELAND, OHIO, ASSIGNOR TO THE BRYANT HEATER & MANUFACTURING COMPANY, OF CLEVELAND, OHIO, A CORPORATION OF OHIO

BOILER CONSTRUCTION

Application filed July 24, 1930. Serial No. 470,275.

This invention relates to boiler constructions, and more particularly to the construction of water heaters adapted to utilize the heat of combustion of gaseous fuels for heating systems for buildings and the like.

It is an object of the invention to provide an improved flue construction for conducting the gases of combustion from the interior of the boiler to the chimney.

10 Other objects and features of novelty will be apparent as the following description proceeds, reference being had to the accompanying drawing, in which

Fig. 1 is a vertical section through a boiler according to the preferred embodiment of the present invention.

Fig. 2 is a transverse section taken along the line 2—2 of Fig. 1.

Fig. 3 is a similar section taken along the 20 line 3—3 of Fig. 1.

Fig. 4 is an elevation of the upper part of the front wall of the boiler shown in Fig. 1 and

Fig. 5 is a detailed perspective view of the 25 baffle plate employed in the novel flue construction.

Referring more particularly to the drawing the boiler comprises a plurality of water sections 10, preferably of cast-iron. Four of 30 these sections have been illustrated in Figs. 2 and 3, but it is to be understood that a greater or less number may be employed as desired. The sections are connected by an upper manifold 11 and lower manifolds 12 and 13. The 35 upper corners of the sections are provided with flanges 14 and 15, and vertical flanges 16 and 17 are provided at the bottom of the sections above the respective manifolds 12 and 13. When the sections 10 are arranged 40 side by side with the flanges 14, 15, 16 and 17 in respectively abutting relationship, the sections may be held together by rods 18 so as to form a unit.

The boiler unit thus described is enclosed 45 within a casing comprising a top plate 19, inner and outer front walls 20 and 21, a rear wall 22, and side walls 53 and 54. Each of these walls, with the exception of the outer front wall 20, are lined with insulating material indicated at 23. The sections 10 are

supported within the casing by a suitable base of which the front plate 24 and the back plate 25 are shown.

The outer front wall 20 is provided with a lower door or the like 26 which provides access to a gas manifold 27 mounted in the space between the inner and outer front walls 20 and 21, preferably between the front plate 24 and the door 26. The manifold 27 supplies gas to a plurality of burners 28 carried by branch pipes 29 projecting through apertures 30 in the front plate 24. A suitable mixing device 31 is provided for each of the burners 28 and a control device such as a valve 32 is provided for each of the branch pipes 29.

The top plate 19 of the casing is provided with an aperture 33 which is adapted to be connected to the chimney for the disposition of spent gases of combustion. The rear wall 22 is provided with an aperture 34, and a hood 35 depends below the lower edge of the aperture 34. The inner front wall 31 is provided with a similar aperture 36, and a similar aperture 37 is provided in the outer front wall 20. The apertures 36 and 37 are connected by an upper curved plate 38 and a lower curved plate 39 to provide a passage which is separate from the space between the inner and outer walls 20 and 21. The outer aperture 37 is preferably screened by foraminous material 46.

The flow of air and gases within the casing is controlled largely by the baffle plate 40 shown in Fig. 5. Flanges 41 and 42 are bent down at each end of the plate 40, and the central portion of each flange is cut away as at 43 preferably along a circular arc which extends through the greater part of the depth of the flange 41 at a point intermediate its ends. The plate 40 is so formed, preferably by folding longitudinally as at 44, as to provide sloping side portions.

The plate 40 is positioned in the space between the sections 10 and the top plate 19, with the flanges 41 resting on the end sections being held against lateral movement by retaining means, such as projections 45 on the end sections. In this position the cut away portion 43 will fit fairly snugly over the 50

manifold 11. Thus the baffle forms a passage having its ends substantially in alignment with the air openings 34 and 36.

In operation, after the burners 28 have been ignited, the gases of combustion will flow upwardly through the spaces between the boiler sections and pass between the flanges 14 and 15 and on each side of the manifold 11. The plate 40 will deflect the gases of combustion laterally and the draft from the chimney through the opening 33 will draw the same around the ends of the plate 40 and up to the chimney. When for any reason the chimney exerts an abnormally strong draft, the same will merely draw air in through the openings 34, 36 and 37 which will prevent the draft from interfering with the operation of the burners 28. Conversely, however, if for any reason a back draft is created, the same will not interfere with the burners 28, but instead will be directed laterally by the plate 40 to the openings 34, 36 and 37.

While one embodiment of the invention has been illustrated and described in such detail as to enable anyone skilled in the art to practice the invention, nevertheless, it is to be understood that the invention is not to be limited to any of the details disclosed other than as necessitated by the development of the prior art; but instead the invention embraces such embodiments of the broad idea as fall within the scope of the appended claims, it being obvious that various changes may be resorted to with respect to the disclosed embodiment without departing from the spirit of the invention.

Having thus described my invention I claim:

1. In a boiler having vertical water sections, the combination of a casing enclosing the sections, said casing having an opening in its upper wall adapted to communicate with a chimney, the opposing vertical walls of said casing which are normal to the plane of the sections having relief openings and means in said casing for deflecting back drafts from said first mentioned opening away from the interior of the boiler and toward said relief openings, or for deflecting products of combustion from the interior of the boiler laterally toward said relief openings.

2. In a boiler having vertical water sections, the combination of a casing enclosing the sections, said casing having an opening in its upper wall adapted to communicate with a chimney, the opposing vertical walls of said casing which are normal to the plane of the sections having relief openings, and means in said casing for deflecting back drafts from said first mentioned opening away from the interior of the boiler and toward said relief openings.

3. In a boiler having vertical water sections, the combination of a casing enclosing

the sections, said casing having an opening in its upper wall adapted to communicate with a chimney, the opposing vertical walls of said casing which are normal to the plane of the sections having relief openings, and a baffle in said casing for deflecting back drafts from said first mentioned opening away from the interior of the boiler and toward said relief openings.

4. In a boiler having vertical water sections, the combination of a casing enclosing the sections, said casing having an opening in its upper wall adapted to communicate with a chimney, the opposing vertical walls of said casing which are normal to the plane of the sections having relief openings, and means in said casing resting on said sections for deflecting back drafts from said first mentioned opening away from the interior of the boiler and toward said relief openings.

5. In a boiler having vertical water sections, the combination of a casing enclosing the sections, said casing having an opening in its upper wall adapted to communicate with a chimney, the opposing vertical walls of said casing which are normal to the plane of the sections having relief openings, a baffle in said casing for deflecting back drafts from said first mentioned opening away from the interior of the boiler and toward said relief openings, and retaining means associated with said sections and cooperating with said baffle.

6. In a boiler having water sections, the combination of a casing enclosing the sections, said casing having an opening adapted to communicate with a chimney, different walls of said casing having air openings, and a baffle in said casing forming a passage having its ends in substantial alignment with said air openings.

In testimony whereof, I hereunto affix my signature.

WILLET E. STARK.
